UNITED STATES PATENT OFFICE.

MARCUS M. ENGEL, OF BRIDGEPORT, CONNECTICUT, ASSIGNOR OF ONE-HALF TO
MAX ZIGUM, OF BRIDGEPORT, CONNECTICUT.

BOTTLE CAPPER.

Application filed March 27, 1924. Serial No. 702,205.

To all whom it may concern:

Be it known that I, MARCUS M. ENGEL, a citizen of the United States, residing at Bridgeport, county of Fairfield, State of Connecticut, have invented a new and useful ⁵ Bottle Capper, of which the following is a specification.

An object of this invention is to provide an improved bottle capper, particularly for ¹⁰ manual operation, which will be very simple in construction involving a minimum number of parts, which will be strong in construction so that it is not liable to be easily gotten out of order or broken and which ¹⁵ may be easily and quickly assembled or disassembled without any machining operations whatever. It may thus be manufactured at low cost, and may be easily and quickly assembled for use and disassembled for shipping or storing.

With the foregoing and other objects in view, I have devised the construction illustrated in the accompanying drawing showing the preferred embodiment of my ²⁵ invention, and which drawing forms a part of this specification. In this drawing,

Fig. 1 is a side elevation of my improved capper showing the method of use.

Fig. 2 is a front elevation looking from ³⁰ the right of Fig. 1.

Fig. 3 is a top plan view.

Fig. 4 is a transverse section substantially on line 4—4 of Fig. 3, but showing the lever in an upright position.

Fig. 5 is a front elevation looking from ³⁵ the left of Fig. 4 and with the rack bar removed.

Fig. 6 is a side elevation of the block and lever removed from the rack bar and showing the first movement in the operation of ⁴⁰ removing the lever from the block.

Fig. 7 is a similar view showing the final movement in removing the lever from the block, and

Fig. 8 is a detailed sectional view showing ⁴⁵ the mounting for the lever.

My improved bottle capper comprises a rack bar 10 including a rack having suitable teeth 11, and preferably having spaced supporting elements 12 at its lower end connected by a cross bar 13 for securing the rack bar to a suitable support, such as a bench or table, but preferably to a base 14. This bar may be secured to the base by any ⁵⁰ suitable means, but the base is preferably

provided with a transverse groove 15 in which the cross bar 13 is seated and secured by suitable bolts 16. The separation of the supports 12 allows a portion of the bottle being operated on to extend between them, ⁶⁰ and thus the positioning of the bottle nearer to the rack bar, giving greater leverage on the capping device and a more easily operated capper.

Mounted to slide on the rack bar, preferably by a pair of spaced guides 17 and 18, is a block 19 including at its lower side an inverted cup 20 forming the capper adapted to press the cap onto the top of the bottle. The rack bar is preferably rectangular in ⁷⁰ cross section to prevent turning of the block about the bar. The block comprises spaced side members 21 connecting the guides 17 and 18, and preferably in one piece therewith and with the capper 20. The operating lever 22 is pivotally mounted between these side members, and is provided at its inner end with means for engaging the rack to reciprocate the block and the capper toward and from the bottle. This means preferably ⁷⁵ comprises a segmental gear 23 meshing with the rack.

I have provided an improved means for mounting this lever so that it may be assembled or disassembled without any machining operations, but still will be retained in proper operative position. For this purpose the side members 21 of the block are provided on their inner sides with opposed recesses 24 open at one side, preferably to ⁸⁵ the rear or toward the rack bar, as shown at 25. The lever is provided with trunnions 26 projecting from opposite sides thereof, and adapted to seat in these recesses and turn therein as the lever is operated. These trunnions are preferably formed in one piece with the lever which may be of any desired shape, but preferably is substantially I-shaped, as shown as this gives the required strength with a relatively small amount of ⁹⁰ material. Means is provided for retaining the trunnions in the bearing recesses. For this purpose the side members 21 are provided on the opposite sides thereof from the open side 25 of the recesses with curved surfaces 27 struck on the arc of a circle substantially concentric with the centers of the trunnions, and the lever is provided with a transverse pin 28 or one or more lugs projecting laterally from the lever, and adapted ⁹⁵ ¹⁰⁰ ¹⁰⁵ ¹¹⁰

to engage the curved surfaces 27 during normal operating of the lever to retain the trunnions in the recesses 24. In order to allow easy insertion and removal of the lever, the 5 side members 21 are provided with opposed grooves 29 so located that the pin or projections 28 will be brought into alignment therewith only when the lever is given normal operation and after the trunnions 26 10 have been removed from the recesses 24, as shown in Figs. 6 and 7.

The operation is as follows:

It is apparent that by swinging the free 15 end of the lever up and down the coaction of the segmental gear 23 with the rack 11 will reciprocate the block carrying the capper 20, and it may be used to press the caps over 20 the tops of the bottles. It will also be apparent that this arrangement gives a relatively 25 large leverage ratio so that a relatively small force on the free end of the lever will apply a relatively large force to the cap giving easy operation. During the normal movements of the lever the segmental gear 30 is in mesh with the rack. If it is desired to adjust the block and capper on the rack bar for use on bottles of different heights, all that is necessary is to swing the lever to a substantially vertical position such 35 as shown in Fig. 4. This is an abnormal position, but it will be noted that when in this position the segmental gear is out of mesh with the rack, and therefore, the block and capper may be slid along the rack bar 40 to any desired position or removed entirely from the bar. After the block is removed from the bar the lever may be removed from the block, as shown in Figs. 6 and 7. By first swinging the free end of the lever downwardly about the pin or projections 28 the trunnions 26 are moved out of the recesses 24 through the open sides 25, as shown in 45 Fig. 6. The pin or projections 28 may then be passed through the grooves 29, as shown in Fig. 7, and the lever removed bodily from the block. Of course, in assembling 50 these operations are merely reversed, and it will be apparent that the lever may be placed in or removed from its operative position in the block without any machining operations whatever, or the heading over of a pivot pin as in the usual construction. It will thus be apparent that this whole 55 device is extremely simple, involving a minimum number of parts, and that these parts may be assembled for use or disassembled for storing, shipping or repair by simple operations which may be performed by anyone.

Having thus set forth the nature of my invention, what I claim is:

1. In a device of the character described, a bottle support, a rack bar extending therefrom, a block including a capper slideable on said bar, said block having spaced side mem-

bers provided with opposed recesses open on their sides toward the rack, and a lever having laterally projecting trunnions seated in said recesses and insertable in and removable from said recesses through the open sides thereof, said lever having a segmental gear adapted to mesh with the said rack. 70

2. In a device of the character described, a bottle support, a rack bar extending therefrom, a block including a capper slideable on said bar, said block having spaced side members provided with opposed recesses open toward the rack, a lever having laterally projecting trunnions seated in said recesses, 75 said lever having a segmental gear adapted to mesh with the said rack, one of the side members of the block being provided with a curved surface on the opposite side from the rack substantially concentric with the center of oscillation of the lever, and a pin carried by the lever coacting with said curved surface during normal operation of the lever to retain the trunnions in said recesses. 80

3. In a device of the character described, 90 a bottle support, a rack bar extending therefrom, a block including a capper slideable on said bar, said block having spaced side members provided with opposed recesses open toward the rack, a lever having laterally projecting trunnions seated in said recesses, 95 said lever having a segmental gear adapted to mesh with the said rack, one of the side members of the block being provided with a curved surface on the opposite side from the rack substantially concentric with the center of oscillation of the lever, and a pin carried by the lever coacting with said curved surface during normal operation of the lever to retain the trunnions in said recesses, the said side member of the block being also provided with a slot for passage 100 of said pin to allow removal of the lever from the block. 105

4. In a device of the character described, 110 a bottle support, a rack bar extending upwardly therefrom, a block including a capper slideable on said bar, said block comprising spaced side members provided with opposed recesses open at one side thereof, a 115 lever having trunnions on opposite sides thereof and adapted for insertion in the open sides of said recesses, one of the side members being provided with a curved surface on the opposite side of its recess from the open side, means carried by the lever coacting with said curved surface to retain the trunnions in the recesses, and means carried by the lever coacting with the rack to reciprocate the block on the bar. 120

5. In a device of the character described, 125 a bottle support, a rack bar extending upwardly therefrom, a block including a capper slideable on said bar, said block comprising spaced side members provided with op-

posed recesses open at one side thereof, a lever having trunnions on opposite sides thereof and adapted for insertion in the open sides of said recesses, one of the side members being provided with a curved surface on the opposite side of its recess from the open side, means carried by the lever coacting with said curved surface to retain the

trunnions in the recesses, said side member being also provided with a groove for passage of said securing means to allow removal of the lever from the block, and means carried by the lever coacting with the rack to reciprocate the block on the bar. ¹⁰

In testimony whereof I affix my signature.

MARCUS M. ENGEL.
